UNITED STATES PATENT OFFICE.

VICTOR GOTTFRED WICKBERG, OF KENYON, MINNESOTA.

TRICK-CASE.

1,266,647.

Specification of Letters Patent.

Patented May 21, 1918.

Application filed May 1, 1916. Serial No. 94,524.

To all whom it may concern:

Be it known that I, VICTOR G. WICKBERG, a citizen of the United States, residing at Kenyon, in the county of Goodhue and State 5 of Minnesota, have invented certain new and useful Improvements in Trick-Cases; and I do hereby declare the following to be a full, clear, and exact description of the invention, such as will enable others skilled in the art 10 to which it appertains to make and use the same.

My invention relates to improvements in trick cases, intended to hold various different articles but especially adapted for 15 cigars; and, to this end, generally stated, the invention consists of the novel devices and combinations of devices hereinafter described and defined in the claim.

In the accompanying drawings, which 20 illustrate the invention, like characters indicate like parts throughout the several views.

Referring to the drawings:

Figure 1 is a view partly in elevation and partly in longitudinal central section;

25 Fig. 2 is a section taken on the line $x^2 x^2$ of Fig. 1, some parts being shown in different positions by means of broken lines;

Fig. 3 is a plan view of the case with the main drawer pulled out, some parts being 30 shown in section;

Fig. 4 is a view corresponding to view 3 with the exception that the supplemental or trick drawer is pulled out of the case and into the main drawer;

35 Fig. 5 is a transverse section taken on the line $x^5 x^5$ of Fig. 1; and

Fig. 6 is a view corresponding to Fig. 5 with the exception that the lock plate is shown in an operative position.

40 The numeral 1 indicates a sheet metal case open at one end and having at its closed end a pair of laterally spaced plates 2, which extend transversely of said case and afford, therebetween, a latch plate guide 3. The 45 inner plate 2 is spaced apart from the closed end of case 1 to afford, therebetween, a cavity 4. A pair of alined holes 5 is formed at the central portions of the plates 2.

Slidably mounted in the case 1 is a main 50 drawer 6 open at its rear end and having on its bottom a stop flange 7, arranged to engage a stop bead 8 on the bottom of the case 1, when the main drawer 6 is drawn part way out, to limit its outward movement 55 from said case. If it is desirable to completely remove the main drawer 6 from the

case 1, the same may be done by lifting said main drawer above the bottom of the case 1, a distance sufficient to carry the flange 7 above the bead 8.

In the head of the main drawer 6 is an inner compartment 9 and an outer compartment 10, separated one from the other, by a perforated partition plate 11. Absorbent material 12, of any suitable kind, is placed 60 within the inner compartment 9 for holding water or other liquid provided for keeping the interior of the case 1 moist. As the liquid evaporates, a new supply may be added from time to time by pouring liquid 65 into the outer compartment 10 and allowing the same to seep through the perforated partition 11 onto the absorbent material 12.

A trick or supplemental drawer 13 is mounted for movement within the case 1 and 70 main drawer 6 and has frictional sliding contact within said main drawer. The frictional contact between the two drawers is such that when the main drawer 6 is drawn out of the case 1, the supplemental drawer, 75 mounted therein, will also be drawn out of the case and from all appearances would seem to be a part of the main drawer 6.

To lock the supplemental drawer 13 to the case 1, at will, and hence prevent its 80 being withdrawn from the case 1, under the frictional contact between the two drawers, I provide a latch arranged to be actuated by turning the case 1 into different positions. This latch comprises a headed stud 14 and a 85 latch plate 15. The headed stud 14 is rigidly secured to the inner end of the supplemental drawer 13, projecting rearward therefrom and, when the said supplemental drawer is 90 within the case 1, projects through the alined holes 5 with its body portion extending transversely of the latch plate guide 3 and with its head extending into the cavity 4. The latch plate 15 is slidably mounted in the 95 guide 3 and one end thereof is bifurcated to afford a pair of diverging prongs 16, which straddle the headed stud 14 when the same projects through the alined holes 5.

Fig. 5 shows the case 1 turned into a position to cause the latch plate 15 to move into 100 an inoperative position under the action of its own weight. In this position on the latch plate 15, the head of the stud 14 is free to move between the prongs 16, allowing the supplemental drawer 13 to be moved into 105 and out of the case 1 while within the main drawer 6. In Fig. 6 the case 1 is shown

turned into a position to cause the latch plate 15 to move, under its own weight, into a position where its prongs 16 are engaged by the head of the stud 14, which locks the supplemental drawer 13 to the case 1. In Fig. 4 the supplemental drawer 13 is shown filled with cigars Z.

While the improved trick case affords excellent means for carrying cigars, without danger of breaking the same, it also affords considerable amusement as well as protects the owner against having to hand out a cigar each time one of his friends happens to ask him for one. As to the amusement afforded by the invention, the owner of one of the trick cases can open the same, and show one of his friends a case full of cigars. Then by closing the main drawer and at the same time turning the case 1 sufficiently to cause the latch plate 15 to move into interlocking engagement with the headed stud 14, the supplemental drawer 13 is locked in the case 1 without attracting his friend's attention to the operation. Upon again opening the main drawer 6, he shows his friend an empty case.

On the other hand, if some one asks the owner of the trick case for a cigar, he can upon taking the case out of his pocket, lock

the supplemental drawer 13, containing the 30 cigars, to the case 1 in a manner previously described, and then open the main drawer 6 and show his friend the empty case.

What I claim is:

The combination with a case having a main drawer and a compartment in the head of said main drawer, of a supplemental drawer mounted for movement within the case and main drawer and having a headed stud on its inner end, the head of the supplemental drawer extending into said compartment, a pair of laterally spaced guide plates in the inner end of the case and having a pair of aligned holes through which said headed stud projects when the supplemental drawer is closed, and a bifurcated lock plate mounted between said guide plates for movement to and from a straddled position on the lock stud when the same is inserted through said two holes in the guide plates.

In testimony whereof I affix my signature in presence of two witnesses.

VICTOR GOTTFRED WICKBERG.
